UNITED STATES PATENT OFFICE.

ROBERT E. MANLEY, OF YORK, PENNSYLVANIA.

PRESS.

1,291,582.

Specification of Letters Patent. Patented Jan. 14, 1919.

Application filed July 5, 1917. Serial No. 178,694.

To all whom it may concern:

Be it known that I, ROBERT E. MANLEY, a citizen of the United States, residing at York, in the county of York and State of Pennsylvania, have invented certain new and useful Improvements in Presses; and I do hereby declare the following to be a full, clear, and exact description of the same, reference being had to the accompanying drawings, forming part of this specification.

This invention relates to a press which is especially adaptable for use in automobile repair shops and garages. The essential object in view is the provision of a press of exceedingly simple and cheap, though strong construction, both as regards the framework of the press and the operating parts, which press is rapid in action when operating on light work and is capable of developing exceedingly heavy pressures when operating on heavy work.

With the above and other objects in view, the invention consists in certain constructions, arrangements and combinations of parts hereinafter described in a preferred form and particularly pointed out in the claims at the end of the specification.

In the drawings,—

30. Figure 1 is a front elevation of a press constructed in accordance with the present improvements.

Fig. 2 is a vertical sectional elevation of the same on the line 2—2 of Fig. 1.

35. Fig. 3 is a top plan view of the press.

Fig. 4 is a horizontal section through the upper frame taken in a plane indicated by the line 4—4 of Fig. 1.

40. Fig. 5 is a horizontal section through the lower frame taken in a plane indicated by the line 5—5 of Fig. 1.

Fig. 6 is a detail vertical sectional elevation of the screw and its operating parts, on the line 6—6 of Fig. 3.

45. Fig. 7 is a detail vertical sectional elevation on the line 7—7 of Fig. 4, illustrating the mode of operating the screw when used for developing high pressures in connection with relatively heavy work.

50. Like characters of reference in the several figures indicate the same parts.

In accordance with the present invention, the main frame of the press is constructed substantially of bars of commercial cross section, for example, channel bars, such as can readily be purchased in the open mar-

ket, quickly cut into the proper size, and assembled to produce a frame of great strength, though of minimum cost. The main frame of the press consists essentially of a relatively wide portion, which may be termed the lower frame A, and a relatively narrow upper portion or frame B mounted upon and supported by the lower frame. Said main press frame is constructed in the following manner: The lower frame A consists of spaced lower vertical channel bars 3 and 4 which are mounted on suitable ground supports 1 and 2, and are connected together at their upper ends by spaced horizontal channel bars 5—5 respectively, secured rigidly to the opposite flanged portions 3^a 4^a of the vertical bars 3, 4. Secured to and positioned between the horizontal bars 5, 5 of the lower frame are upper vertical bars 6, 7, which are, in turn, connected together at their upper ends by horizontal bars 8, 8, secured to the flanged portions 6^a, 7^a of said bars 6, 7. The bars 6, 7 and 8, 8 constitute the upper frame B, and the latter is made considerably narrower than the lower frame by positioning the upper bars 6, 7, some distance between the lower bars 3, 4, as shown more particularly in Fig. 1. That portion of the horizontal bars 5, 5, which is located between the vertical bars 6, 7, constitutes a table C for supporting relatively narrow or small articles to be operated upon by the press mechanism, as will hereinafter appear. In order to adapt the press for use with wider or larger articles than could be accommodated between the bars 6, 7, the lower frame is provided with a lower table D, preferably mounted so as to be capable of vertical adjustment relatively to the lower frame. The lower table D is constructed of a pair of spaced horizontal channel bars 9, 9 connected together by means of short lateral bars 10, 10 and further braced laterally by angularly extending bars 11, 11, as shown in Fig. 5. The horizontal bars 9, 9 overlap the flanged portions 3^a, 4^a of vertical bars 3, 4, and are supported by laterally-extending pins 12 mounted in holes 13 formed in said flanged portions. Each bar 3, 4, is provided with a vertical series of spaced holes 13, permitting adjustment of the pins 12 to different heights and corresponding adjustment of the lower table D.

As will hereinafter appear, the press is

2
capable of developing tremendous pressures, and in order to brace the lower table D when operating with large articles, such, for example, as a vehicle wheel positioned on the 5 lower table, there are provided an adjustable brace rods 14 connecting the upper and lower tables together. Said brace rods are screw threaded at their upper and lower ends, as shown at 14^a 14^b, which ends are respectively 10 provided with nuts 15, 16, for adjusting upper and lower cross pieces 17 and 18 adapted respectively to engage the top and bottom faces of the upper and lower tables. The brace rods 14 extend between the bars 15, 5, 9, 9, and greatly augment the resistance 15 of the bars 9, 9 to heavy strains, such as would be produced when operating the press with the hereinafter described high leverage connections on an object, a wheel or example, supported upon the bars 9, 9. In practice, the brace rods 14 are adjusted as near the center of the bars 9, 9, as possible; when operating on a wheel, this may be accomplished by removing nuts 15 and cross-pieces 20 25 17, then removing the rods 14 and positioning the rod between two of the spokes and close to the hub of the wheel. After the rods have been thus positioned with their upper ends projecting through between the 30 bars 5, 5, at points intermediate the upright bars 6, 7, the cross pieces 17 can be replaced and the rods again secured to the frame by the nuts 15.

If desired, the lower frame A of the main 35 press frame may be rendered additionally secure by angularly-extending bracing rods 19, 19, respectively, connecting the upper ends of the vertical bars 3, 4, with the outer ends of the ground supports 1, 2. The lower 40 frame may be further braced by means of a longitudinally extending bracing bar 20^a connecting said ground supports and the bars 3, 4, together, is shown in Fig. 1.

The improved press mechanism of the 45 present invention will now be described.

Centrally supported between the upper horizontal bars 8-8 of the upper frame B is a bearing 20 adapted to receive a vertically disposed screw 21. The screw is provided with an axially extending groove 22 which receives a key 23 supported by the bearing 20 for the purpose of holding the screw against rotation relatively to the frame, while permitting axial or vertical 50 movement of the screw. The screw constitutes the pressure transmitting member of the press and its lower end is adapted for the attachment of various devices for operating on articles supported upon the press 55 frame, and for this purpose the lower end of the screw is provided with a horizontally extending peripheral groove 24 adapted to receive the locking member, for example, a small screw mounted in a device attached to 60 the lower end of the screw 21. The most

common of the devices which are attached to the lower end of the screw 21 are a spindle nose 25 which is employed when operating the press in connection with a shaft or tubing supported upon upper table C, and an extension rod or piece 26 which is utilized when operating on an object supported by the lower table D. One of the particular uses of the extension rod is for pressing a bearing out of a vehicle wheel. 75

The screw 21 is operated, *i. e.*, moved vertically with respect to the main press frame by means of a horizontal nut 27 rotatably mounted on the screw but held against substantial vertical or axial movement with respect to the main press frame. For the latter purpose the nut is provided with a sleeve-like portion 28 of relatively reduced diameter and formed in said sleeve-like portion is a horizontally extending annular groove 85 29 which receives a fixed stop or extension 30 of the bearing 20, so as to prevent longitudinal movement of the nut 27. Preferably, the annular groove 29 is made somewhat wider than the extension 30, thereby 90 permitting the nut 27 and screw to yield somewhat vertically. The upper end of the screw 21 is adapted to project beyond the horizontal bars 8-8 of the upper frame, and the loose mounting above described permits 95 a slight vertical movement of the screw. As the upper end of the screw is exposed, a sharp blow applied to the upper end of the screw by hammer or mallet may readily be 100 transmitted by the screw to loosen or dislodge parts firmly stuck or frozen to the article from which it is desired to remove them. With the above construction, it will be obvious that rotation of the nut is effective to impart an axial or vertical movement 105 to the screw 21.

In accordance with the invention, power for rotating the nut may be transmitted in either of two ways, (1) by a quick action leverage system when it is desired to operate the parts in connection with relatively light work, or in cases where the development of excessive pressure is unnecessary, (2) or by a high power or relatively slower acting leverage system in cases where it is 115 necessary to develop the highest pressures possible. Formed on the nut 27 is an annular ring-like portion 31 relatively larger in diameter than the sleeve-like portion 28 of the nut and provided with a horizontally 120 extending annular series of teeth 32, which teeth are cut clear to the periphery of the ring-like portion, as shown. In order to impart a rotary movement to the nut 27 when operating the latter according to the 125 first leverage system above set forth, there is provided an actuating bar or handle 33 having an arcuate tooth 34 at its inner end, the tooth being adapted to fit in the annular groove 29 of the sleeve-like portion 28 of 130

the nut, when the actuating bar is applied. Said actuating handle is further provided with notches 35, which permit the handle to be brought into engagement with one of the 5 teeth 32 of the ring-like portion 31 of the nut. When not in use the handle may be readily detached from the nut. When applied so as to occupy a radial position with respect to the ring-like portion, in the manner shown in the drawings, a back and forth movement of the actuating handle in a substantially horizontal plane will be effective to transmit a relatively rapid axial movement to the screw 21, the handle being held 10 in engagement with the tooth during the forward movement and elevated out of engagement on the return movement. While the action of the press is quite rapid in operating the same by applying the handle in this manner, it will be found that a 1000 to 20 1 leverage may be developed.

The following connections are employed in the high power leverage system: Pivot- 25 ed in a suitable vertical bearing 36 supported by the vertical bar 7 of the upper press frame is a bell crank lever 37, the arms 37^a and 37^b of which are movable in substantially horizontal planes. A reciprocating operating bar 38 is pivoted to the end of 30 the arm 37^a of the bell crank lever, and said operating bar 38 is provided with a slot 39 which receives a fixed guiding and supporting member 40 suspended from one of the horizontal bars 8-8 at the top of the upper 35 frame B. A back and forth movement of the bell crank lever of course imparts a reciprocating movement to the horizontal bar 38, and the latter motion is utilized to transmit a step-by-step movement to the actuating nut 27 through the ring-like portion 31 of the latter. In order to effect this result, the operating bar 38 is formed with a socket 41 in which is loosely mounted a 40 pawl 42 adapted to engage a tooth 32 of the ring-like portion 31. On forward movement of the operating bar 38, the pawl imparts a one-step movement to the ring-like portion 31 of the nut 27, and on return movement of said operating bar 38 the pawl 45 45 yields upwardly in its socket 41, so as to pass over the next tooth of said ring-like portion. The arm 37^b of the bell crank lever is formed with an elongated socket 43 which is adapted for the reception of an actuating handle, such as the handle 33. The end of the handle 33 opposite to the ar- 50 55 cuate tooth 34 may be inserted in the socket 43 and the bell crank lever oscillated back and forth, as indicated above, to impart a step-by-step movement to the actuating nut.

In operating the screw 21 in accordance with the last mentioned system of levers, the progression of the screw is relatively slow but enormous pressures can be de- 60 65 veloped. For example, it is quite possible

to obtain a leverage of approximately 2200 to 1. When a high power leverage system is not in use, the pawl 42 may be lifted out of engagement with the teeth 32 and so retained by positioning a small lateral pin 42^a carried by the pawl over a retaining projection 42^b formed on the upper face of the operating bar 38, which holds the pawl in elevated position.

As will be noted, the above described press is exceedingly simple in construction and operation. The various parts constituting the frame may be secured together by any suitable fastening devices, for example, ordinary bolts and nuts of proper strength 75 80 may be employed for securing together the various bars constituting the frame. The utility of the press is furthermore not limited to the employment of the press mechanism above described. For example, the upper table C may be utilized as a work bench 85 for any of the numerous uses found in machine shops and garages.

As shown in Fig. 1, the vertical bars 6, 7, are secured at top and bottom to the bars 8, 5, by means of detachable fastening devices such as nuts and bolts. By removing the pair of the bolts from the upper end of one of said bars 6, 7, and one bolt from the lower end thereof, the bar may be swung 90 outwardly on its lower bolt, as a pivot. This permits the insertion of an open frame larger than the upper frame of the press in the space between the bars 6, 7, for example, when it is desired to operate the 100 press in conjunction with an inner portion of a large frame. If at least one end of the bars 6, 7, were not removable in the above set forth manner, this highly advantageous feature would not be present. 105 After a large frame has been thus slipped into position for being operated on by the press, the displaced bar may be shifted back into position and again secured by reapplying the bolts. The above operation is re- 110 peated when it is desired to remove the frame from the press.

What is claimed is:

1. In a press, the combination of a main press frame constructed substantially entirely of bars of commercial cross section and comprising a wider frame including spaced lower vertical bars connected at their upper ends by spaced horizontal bars, the latter constituting a table, and a relatively 115 120 narrow upper frame including spaced upper vertical bars mounted on the horizontal bars of the lower frame between the vertical bars of the latter and said upper vertical bars connected at their upper ends by horizontal bars; and a press mechanism supported by the horizontal bars of the upper frame.

2. In a press, the combination of a main press frame constructed substantially en- 130

1
tirely of bars of commercial cross section and comprising a wide lower frame including spaced lower vertical bars connected at their upper ends by spaced horizontal bars, the latter constituting an upper table, a 5 lower table substantially equal in width to the lower frame and adjustably supported thereon so as to be capable of vertical adjustment with respect to the upper table, and a relatively narrow upper frame including spaced upper vertical bars mounted on the horizontal bars of the lower frame between the vertical bars of the latter and said upper vertical bars connected at their 10 upper ends by horizontal bars; and a press mechanism supported by the horizontal bars of the upper frame.

3. In a press, the combination of a main press frame constructed substantially entirely of bars of commercial cross section and comprising a wider lower frame, including spaced lower vertical bars connected at their upper ends by spaced horizontal bars, the latter constituting an upper table, a 20 lower table substantially equal in width to the lower frame and adjustably supported thereon so as to be capable of vertical adjustment with respect to the upper table, a vertically and horizontally adjustable bracing member connecting the upper table 25 with the lower table and interposed between the vertical bars of the lower frame, and a relatively narrow upper frame including spaced upper vertical bars mounted on the horizontal bars of the lower frame 30 between the vertical bars of the latter and said upper vertical bars connected at their upper ends by horizontal bars; and a press mechanism supported by the horizontal bars of the upper frame.

4. In a press, the combination of a main press frame constructed substantially entirely of bars of commercial cross section and comprising a wide lower frame, including spaced lower vertical bars connected at their upper ends by spaced horizontal bars, the latter constituting an upper table, a lower table comprising horizontal bars bridging the space between the vertical 45 lower bars and adjustably mounted thereon so as to be capable of vertical adjustment with respect to the upper table, and a relatively narrow upper frame including spaced upper vertical bars mounted on the horizontal bars of the lower frame between the 50 vertical bars of the latter and said upper vertical bars connected at their upper ends by horizontal bars; and a press mechanism supported by the horizontal bars of the 55 upper frame.

5. A press of the character set forth, comprising a frame, a vertically-disposed non-rotatable screw movable axially in the frame, and a horizontal screw-operating nut

rotatably mounted on said screw, but held 65 against substantial axial movement with respect to the frame, the nut being provided with an outer ring-like portion of relatively large diameter, formed with a series of teeth disposed in a substantially horizontal 70 plane, and the nut also having a vertical sleeve-like portion of reduced diameter relatively to said ring-like portion, and an actuating lever bar the sleeve-like portion of the nut constituting a bearing for the 75 inner end of the actuating lever bar, said bar being positioned so as to engage a tooth of said ring-like portion, substantially as described.

6. The combination with a press frame, 80 of a vertically-disposed non-rotatable screw movable axially in the frame, a horizontally screw-operating nut rotatably mounted on said screw but held against substantial axial movement with respect to the frame, the nut 85 being provided with an outer ring-like portion of relatively large diameter formed with a series of teeth disposed in a substantially horizontal plane, and the nut also having a vertical sleeve-like portion of reduced 90 diameter relatively to said ring-like portion, and a nut-operating lever engaging said sleeve-like portion extending radially therefrom and also engaging a tooth of the ring-like portion. 95

7. The combination with a press frame, 100 of a vertically-disposed non-rotatable screw movable axially in the frame, a horizontal screw-operating nut rotatably mounted on said screw but held against substantial axial movement with respect to the frame, the nut being provided with an outer ring-like portion of relatively large diameter formed with a series of teeth disposed in a substantially horizontal plane, and the nut also having a vertical sleeve-like portion of reduced 105 diameter relatively to said ring-like portion formed with an annular groove, and a nut-operating lever provided at its inner end with an arcuate tooth adapted to fit in said groove, the lever extending radially from the sleeve-like portion of the nut and also engaging a tooth of the ring-like portion. 110

8. The combination with a press frame, 115 of a vertically-disposed non-rotatable screw movable axially in the frame, a horizontal screw-operating nut rotatably mounted on said screw and formed with a ring-like portion having an annular series of teeth disposed in a substantially horizontal plane; and means for imparting a step-by-step movement to said nut, including a bell crank lever mounted on a vertical axis with both arms of the lever movable in substantially horizontal planes, a reciprocating, horizontally movable operating bar pivoted to one arm of said lever and provided with a pawl adapted to engage a tooth of the ring-like 120 125

portion of said nut, and the other arm of the bell crank lever being adapted to support an actuating handle, substantially as described.

9. The combination with a press frame, of 5 a vertically-disposed non-rotatable screw movable axially in the frame, a horizontal screw-operating nut rotatably mounted on said screw and formed with a ring-like portion having an annular series of teeth disposed in a substantially horizontal plane; and means for imparting a step-by-step movement to said nut, including, a bell crank lever mounted on a vertical axis with both arms of the lever movable in substantially 10 horizontal planes, a reciprocating slotted horizontally-movable operating bar pivoted to one arm of said lever and provided with a pawl adapted to engage a tooth of the ring-like portion of said nut, a fixed guiding and supporting member projecting into the slot of the operating bar, and the other arm of the bell crank lever being adapted to support an actuating handle, substantially as 15 described.
- 20 10. In a press, the combination of a main press frame constructed substantially entirely of bars of commercial cross section and comprising a wide lower frame including spaced lower vertical bars connected at 25 their upper ends by spaced horizontal bars, the latter constituting a table, and a relatively narrow upper frame including spaced upper vertical bars mounted on the horizontal bars of the lower frame between the vertical bars of the latter and said upper vertical bars connected at their upper ends by horizontal bars, one of the upper vertical bars being detachably secured at one end to 30
- 35

the press frame and mounted so as to be capable of pivotal movement at the other 40 end.

11. In a press, the combination of a main press frame constructed substantially entirely of bars of commercial cross section and comprising a wide lower frame including spaced lower vertical bars connected at 45 their upper ends by spaced horizontal bars, the latter constituting a table, and a relatively narrow upper frame including spaced upper vertical bars mounted on the horizontal bars of the lower frame between the vertical bars of the latter and said upper vertical bars connected at their upper ends by horizontal bars, one of the upper vertical bars being secured at top and bottom by 50 removable bolts to the press frame.

12. A press of the character set forth comprising a frame, a vertically-disposed non-rotatable screw movable axially in and adapted to project beyond the upper end of 55 the frame, and a horizontal screw-operating rotatable nut, mounted on said screw and loosely mounted in the frame whereby the nut and screw are capable of a limited vertical movement with respect to the frame, the nut being provided with an outer ring-like portion of relatively large diameter, formed with a series of teeth disposed in a substantially horizontal plane, and the nut also having a vertical sleeve-like portion of reduced diameter relatively to said ring-like portion, and a nut actuating lever bar engaging said sleeve-like portion and positioned so as to engage a tooth of said ring-like portion, substantially as described.

ROBERT E. MANLEY.
